UNITED STATES PATENT OFFICE.

GEORGE A. GILLEN, OF JERSEY CITY, NEW JERSEY, ASSIGNOR TO GILLEN, KIMMEY,
BAKER SYNDICATE, INCORPORATED, OF NEW YORK, N. Y., A CORPORATION.

LOUD SPEAKER.

Application filed March 9, 1925. Serial No. 13,981.

This invention relates to loud speaking telephone receivers such as are commonly used in receiving broadcast programs and the like. The principal object of the invention is to provide a speaker of the class described wherein the diaphragm is mounted between the pole pieces of the magnet in such a manner that its action is cushioned, thereby increasing the quality of reception and reducing the rattling and rasping, commonly experienced in the use of the ordinary loud speaker, to a minimum.

Another object of the invention resides in the provision of an adjustable loud speaker so that it may be readily varied and adapted to the peculiarities of the receiving set in connection with which it is used.

A further object of the invention is to provide a magnetic armature which is acted upon by the variations of the density of the magnetic flux flowing between the pole pieces of the permanent magnet and which is anchored to a diaphragm of any suitable substance either of a magnetic or non-magnetic substance.

With the above and other objects in view, the invention consists in the novel construction, combination and arrangement of parts which will be fully set forth in the following specification, claimed and illustrated in the accompanying drawing in which:—

Fig. 1 is a top plan view of this improved loud speaker.

Fig. 2 is a vertical sectional view taken on line 2—2 of Fig. 1.

Fig. 3 is a similar view taken on line 3—3 of Fig. 1.

Fig. 4 is a perspective view of the magnet, showing fragments of the adjusting screws, and

Fig. 5 is a perspective view of the armature mounting block.

Referring to the drawings in detail, the numeral 10 designates in its entirety the housing and diaphragm support which comprises a pair of hollow semi-spherical members 11 and 12 which are provided at their meeting edges with annular outwardly extending flanges 13 and 14 respectively, and the inwardly extending diaphragm supporting flanges 15 and 16.

The diaphragm 17 is secured between a pair of annular cushioning rings 18 which in turn are clamped between the clamping rings 19 by means of clamping screws 21

which enter the flanges 15 to secure the diaphragm in place as clearly shown in the drawings. Formed centrally of the diaphragm is a boss 22 which is upstruck to form a recess for the reception of the head, 60 of a screw 23 and also a bearing for the end of the armature 24. It will thus be seen that a rigid connection between the armature and diaphragm is in this manner obtained. 65

The end of the armature opposite that which is secured to the diaphragm is pivoted as at 25 in a block 26 which is secured to the flange 13 previously described.

Secured to the inner face of the lower 70 member 11 is a horse-shoe shaped permanent magnet 27 the pole pieces 28 of which are cut away to provide flat faces 29 to which the flattened portions 30 of the cores of the magnets 31 are secured as will be clearly seen 75 upon reference to Fig. 4. These flattened portions 30 are pierced as at 32 to receive the tapered portions of adjusting screws, to be more fully hereinafter described. As shown in the drawings the magnet 27 is thinned as 80 at 33 at the bight portion to permit of a moderate flexing of the same so that the pole pieces 31 may be readily adjusted toward or away from the armature 24.

In order to provide a positive and secure 85 adjustment of the magnet, the members 11 and 12 are provided with diametrically opposed tubular bosses 34 and 35, the axes of which are arranged at right angles to the longitudinal axis of the magnet 27 and substantially in alignment with the openings 32 90 previously mentioned. These bosses 34 and 35 are internally screw threaded and the bosses on one side are provided with bushings 36 which act as guides for the reduced 95 stems 37 formed on the inner ends of the adjusting screws 38. As shown the reduced stem 37 of each screw 38 is joined thereto by a tapered portion 39 which enters the openings 32 so that as the screw is advanced, 100 the poles of the magnet 27 will be spread and drawn away from the armature. Obviously with such an arrangement individual adjustment of the poles is made possible and extremely minute movement of the parts is secured. 105

The upper member 12 is provided with a collar 40 into which the reduced end of a horn may be inserted while the lower member is provided with a stem 41 which enters 110

a collar 42 formed on a suitable base 43 so that the device may be supported in an upright position.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

1. A loud speaking receiver comprising a diaphragm, a permanent horse-shoe magnet, means supporting the diaphragm between the poles of said magnet, pole pieces secured to the poles of the magnet and extending into close proximity to the diaphragm, and adjusting screws for moving the pole pieces away from the diaphragm against the spring tension of the magnet.

2. A loud speaking receiver comprising a diaphragm, a permanent horse-shoe magnet, means supporting the diaphragm between the poles of said magnet, pole pieces secured to the poles of the magnet and being disposed in close proximity to the diaphragm on opposite sides thereof, pierced extensions on said pole pieces, and adjusting screws extending therethrough whereby the distance between the pole pieces and the diaphragm may be varied.

3. A loud speaking receiver comprising a diaphragm, a permanent horse-shoe magnet, means supporting the diaphragm between the poles of said magnet, pole pieces on the poles of said magnet extending into close

proximity to the diaphragm, apertured extensions on the pole pieces, adjusting screws, and tapered extensions on said adjusting screws adapted to enter the apertures in the pole pieces whereby when the screws are advanced, the pole pieces will be moved against the tension of the magnet away from the diaphragm.

4. A loud speaking receiver comprising a diaphragm, a permanent horse-shoe magnet, means supporting the diaphragm between the poles of said magnet, pole pieces secured to the poles of the magnet and being disposed in close proximity to the diaphragm on opposite sides thereof, pierced extensions on said pole pieces, and adjusting screws extending therethrough whereby the distance between the pole pieces and the diaphragm may be varied and an armature secured to the diaphragm in alignment with the pole pieces.

5. A loud speaking receiver comprising a diaphragm, a permanent horse-shoe magnet, means supporting the diaphragm between the poles of said magnet, pole pieces on the poles of said magnet extending into close proximity to the diaphragm, apertured extensions on the pole pieces, adjusting screws, and tapered extensions on said adjusting screws adapted to enter the apertures in the pole pieces whereby when the screws are advanced, the pole pieces will be moved against the tension of the magnet away from the diaphragm and an armature secured to the diaphragm in alignment with the pole pieces.

GEORGE A. GILLEN.
